UNITED STATES PATENT OFFICE

CLIFTON CHISHOLM, OF CLEVELAND, OHIO, ASSIGNOR, BY MESNE ASSIGNMENTS, TO THE AMERICAN MULTIGRAPH CO., OF CLEVELAND, OHIO, A CORPORATION OF DELAWARE

TYPE CASE

Application filed December 8, 1928. Serial No. 324,631.

This invention relates to type cases together with means for loading them at the top so that the type may descend by gravity into the case. More particularly, the invention is concerned with a case having channels with projecting ribs adapted to confine short type, grooved on its opposite sides, such as is used on a multigraph.

The primary object of the invention is to enable the rapid and certain loading of the type case from a temporary holder carrying a row of type. The invention is hereinafter more fully explained in connection with the drawings and its essential characteristics are summarized in the claims.

In the drawings, Fig. 1 is a front elevation of a portion of an upright type case and a loading tube in position for discharging into the case; Fig. 2 is a vertical transverse section thereof, as indicated by the line 2-2 on Fig. 1; Fig. 3 is a cross section through the loading tube and upper portion of the case, as indicated by the line 3-3 on Fig. 2; Fig. 4 is a cross section of the loading tube; Fig. 5 is a fragmentary longitudinal section of the loading tube, as indicated by the line 5-5 on Fig. 4; Fig. 6 is a perspective of a portion of the loading tube, having type therein.

As shown in Figs. 1, 2 and 3, the body of the type case comprises a series of parallel bars or rails 10 spaced apart and held equidistant by suitable means, as for instance by cross plates, of which the upper plate is shown at 14. Each of the rails 10 has ribs 11 at its opposite edges adjacent the front, thus providing under-cut channels in which short grooved type A may be loaded and descend by gravity, the ribs of the bars occupying grooves α in the sides of the type. The rails are preferably I-shaped in cross section, the base portions 12 of the rails seating in grooves 15 in the cross bars.

The type to be loaded are contained in a temporary holder comprising a tube 30 having a longitudinal slot 31 from end to end parallel with the axis of the tube, the edges of this tube adjacent the slot entering the groove α of the type. To prevent the type inadvertently passing out of the tube 30, suit-

able detents 32, adjacent the opposite ends of the tube are provided. These detents are preferably integral tongues cut from the portion of the tube opposite the slot 31 and bent into the tube as shown in Figs. 4 and 5. The tongues project in such direction and have such resilience that the type may be readily slid into place in the tube beyond the tongue along the incline of the tongue, but thereafter are retained by abutting the end of the tongue, which automatically springs back into place.

To discharge type from the tubular holder described into the case, it is necessary to cause the tube slot to align with a slot between ribs of the type case and to press back the detent to free the type in the tube. My type case provides for automatically effecting this release of the type when the tube is brought into registration with the case, as will now be described.

The upper cross plate 14 of the type case projects a material distance above the upper ends of the rails 10, and mounted on this cross plate behind the upper portions of the rails is a comb spring 20 having teeth 21 (one for each type channel) projecting upwardly directly behind prolongations of the type channels. Each spring tongue 21 is rounded forwardly at its upper end as, at 22 in Fig. 2. A cross bar 14 is recessed slightly behind the spring tongues 21, to provide space for insertion of the rear wall of the tube 30 behind any tongue.

In discharging the type from the tube into the desired channel, the tube is simply shoved downwardly over the corresponding tongue 21; that is to say, the base portion of the tube occupies the recess behind the spring tongue 21, and the tongue lies snugly along the inner face of the tube. This tongue is stiffer than the detent 32 of the tube, and thus presses back the detent to release the type. Accordingly, the action of putting the tube in place automatically releases the row of type in the tube, so that they may slide by gravity down the tube and into the type channel corresponding to the tongue. The tongue thus serves the double purpose of

positioning the type tube and of causing the detent to release the type.

In order that the tube may be no heavier than necessary, its thickness is materially less than the height of the grooves *a* in the type, so that these type lie quite loosely on the ribs provided by the tube edges. In discharging the type, it is desirable that their heads lie against the outer face of the tube so that all their grooves will accurately align, and I effect this by arranging the case so that the tube will be tipped backwardly during the insertion, this backward tipping being sufficient to maintain all the type with their heads seated against the outer face of the tube edge. To effect this, I incline rearwardly the forward upper face of the cross bars 14 as shown at 15 in Fig. 2, and I cut off the upper ends of the rails 10 at right angles to such inclined face, and I bend back the tongues 21 of the spring comb so that they are normally substantially parallel with the inclined face 15 of the cross bar.

To enable the tube 30 to be quickly put in place, embracing the spring tongue 21, I preferably taper the sides of these tongues as shown in Fig. 1. I bevel backwardly the upper portions of the ribs 11 and also of the base portion 12 of the rails, as indicated at 17 in Fig. 1 and 18 in Fig. 2 respectively. This causes the upper portion of the type case rails to properly register with the tube, the forward face of the ribs 10 thus aligning with the edges of the tube at the opposite sides of the slot 31 and the forward face of the rear portions 14, clearing the feet of the type. Finally, I taper the top portion of the type case rails, at least as to the front portion thereof, indicated at 19 in Fig. 1.

It will be seen that, when the loaded type tube is shoved downwardly into place embracing the tongue 21, a continuous straight channel is provided for the type from the tube slot to the corresponding type case slot, and the type are free to drop by gravity. The tapering of the sides of the spring tongues provides for easy placement of the tube, and the tapering of the upper ends of the rail ribs removes any possibility of the type catching on the upper ends of the ribs. Experience has demonstrated that with such a type case as described, the tubular carrier may be quickly put in place and will rapidly and effectively discharge its type into the case.

I claim:—

1. The combination with a type case having a plurality of channels down which type may descend by gravity, a holder for a single row of type comprising a tube having a slot parallel with its axis, said tube having within it a detent to normally retain type therein, and mechanism adapted to enter the tube for moving said detent to release

the type when the tube is in registration with a type channel of the case.

2. The combination of a type case having a series of parallel type channels, a holder for a single row of type comprising a tube having a slot parallel with its axis, said tube having a spring tongue cut out from its base portion opposite the slot, and means for automatically pressing said tongue toward the base of the tube to release the type when the tube is brought into registration with a type channel.

3. A type case having a series of parallel channels, a series of tongues associated with the respective channels adjacent their entrance, and said tongues being adapted to coact with a temporary holder for individual type.

4. In a type case, the combination of a series of parallel rails providing channels between them, and a series of tongues projecting beyond the rails from a position adjacent to the back of the type channels.

5. A type case comprising a series of substantially upright rails having ribs providing under-cut channels for grooved type, and a series of spring tongues projecting upwardly from the back of the space between the rails.

6. A type case having in combination parallel rails with projecting ribs for holding grooved type, a cross bar, and tongues carried by the cross bar and projecting upwardly and adapted to be embraced by a tubular type holder registering with a type channel.

7. The combination of a type case having parallel upright rails with ribs providing under cut type channels, tongues projecting upwardly back of prolongations of the channels between the rails, and a tubular type holder adapted to embrace any tongue and be positioned in registration with the corresponding channel.

8. The combination of a type case having parallel upright rails with ribs providing under cut type channels, spring tongues projecting upwardly behind the entrance to the respective channels, and a tubular type holder adapted to embrace any tongue and be positioned in registration with the corresponding channel and having a spring detent pressed to idle position by the spring tongue.

9. In a type case, the combination of a series of parallel rails spaced apart equi-distantly, a cross bar secured to said rails, a comb secured to the cross bar and having spring teeth, the teeth projecting upwardly behind a prolongation of the type channel.

10. A type case comprising a series of parallel I-shaped rails spaced equi-distantly, a cross bar to which said rails are secured, and a comb of spring metal secured to the cross bar and having upwardly projecting teeth, the teeth being behind a prolongation of the space between a pair of parallel rails,

combined with a tubular type holder having a slot parallel with its axis adapted to hold a row of type and having a detent for such row projecting inwardly from the base of the tube, there being a recess in the cross bar behind the tongues into which the tube may pass with the tongue pressing back the detent to release the type while it is in registration with the corresponding channel.

11. The combination of a type case having upright parallel rails, a cross bar secured to the rails, said cross bar extending upwardly higher than the rails and being inclined backwardly, the upper ends of the rails being cut off at substantially right angles to such inclined face of the cross bar.

12. The combination of a type case having upright parallel rails, and a backwardly inclined guide higher than the top of such rails, the upper ends of the rails being beveled backwardly on their front faces.

13. The combination of a type case having parallel rails with projecting side ribs adapted to hold grooved individual type between them, means for positioning a tubular type holder adjacent the upper end of said rails with a channel of the type holder registering with that of the rails, the upper ends of the rail ribs being beveled to gradually widen the channel to the type case, and means for releasing the type in the tube consequent upon its being brought into registration with a channel of the case.

14. The combination with a type case having a plurality of channels, of a separate holder for a row of type, said holder being adapted to be brought into substantial alignment with the case, means for so positioning the holder, and means for thereafter causing the release of the row of type from the holder while the latter is in approximately upright position.

15. A type case having parallel channels down which type may pass by gravity and means associated with each channel and extending above the top thereof for releasing a row of type from a temporary holder while it is in registration with the channel.

16. A type holder having a longitudinal slot adapted to position a row of grooved type and having an internal detent pressed inwardly toward the slot, combined with means providing a channel adapted to receive type from said type holder, and means associated with said channel adapted to enter said type holder and press back the detent to free the type.

17. The combination of a type holder in the form of a tube having a longitudinal slot along it and having an internal retaining tongue carried by the tube on the side opposite the slot and pressed inwardly toward the slot, a channel adapted to receive type from the tubular holder, and a tongue associated with said channel adapted to enter the tube

when the same registers with the channel and press back the retaining tongue to free the type.

18. The combination with a type case having a plurality of channels, a holder for a single row of type, a detent within said holder for normally retaining the type therein, and mechanism carried by the type case and adapted to enter said holder and bear on said detent whereby a longitudinal movement of the holder may move said detent to release the type when the holder is in registration with a type channel of the case.

In testimony whereof, I hereunto affix my signature.

CERTIFICATE OF CORRECTION.

Patent No. 1,800,505.

Granted April 14, 1931, to

CLIFTON CHISHOLM.

It is hereby certified that the above numbered patent was erroneously issued to "The American Multigraph Co., of Cleveland, Ohio, a corporation of Delaware", whereas said patent should have been issued to American Multigraph Co., of Cleveland, Ohio, a corporation of Delaware, as assignee by mesne assignments of the entire interest in said invention, as shown by the records of assignments in this office; and that the said Letters Patent should be read with this correction therein that the same may conform to the record of the case in the Patent Office.

Signed and sealed this 5th day of May, A. D. 1931.
